(57) CLAIM

The ornamental design for a tool cart creeper, as shown and described.

DESCRIPTION

FIG. 1 is a perspective view of a tool cart creeper showing the design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a partial exploded perspective view of the tool cart creeper showing the design.

The broken lines in the drawings depict portions of the tool cart creeper that form no part of the claimed design.
